UNITED STATES PATENT OFFICE.

ARTHUR S. WILY, OF NEW YORK, N. Y.

DESIGN FOR AN IDENTIFICATION-CHECK.

No. 38,419.

Specification for Design.

Patented Jan. 15, 1907.

Application filed December 10, 1906. Serial No. 347,234. Term of patent 7 years.

To all whom it may concern:

Be it known that I, ARTHUR S. WILY, a citizen of the United States, residing in the borough of Manhattan, in the city, county, and State of New York, have invented a new, original, and ornamental Design for Identification-Checks, of which the following is a specification, reference being had to the accompanying drawing, forming part thereof.

The design is a plan view of an identification-check showing my design.

I claim—

The ornamental design for an identification-check as shown.

ARTHUR S. WILY.
